DIE STRUCTURE

Eric Lawrence Wildy and Alexander John Sands,
Westminster, London, EnglandApplication August 3, 1942, Serial No. 453,444,
In Great Britain August 5, 1941

7 Claims. (Cl. 91—53)

It is an object of the invention to provide an improved form of die for carrying out the process, the action of said die being more efficient than those hitherto proposed, and its construction being relatively simple. The invention further contemplates the provision of an improved form of coating machine.

According to the invention the wire or the like, after being coated with viscous medium, is passed through a die comprising a hollow substantially conical cup member supported by a plurality of substantially radial arms which bear with lateral freedom against supporting surfaces to limit movement of the die in the direction of travel of the wire, said wire leaving the die through an orifice in the apex of the cup member, whereby the action of the coating material within the cup member serves to centralise the orifice relative to the wire. Conveniently the bearing surfaces which are engaged by the radial arms are disposed in a plane which intersects the wire at a position in advance of the die orifice, whereby the coating material draws the die to a position of stable equilibrium.

There is further provided according to the invention a die for regulating the thickness of viscous coatings applied to wires and the like, comprising an inverted cup having a substantially conical interior and an orifice at its apex, said cup being formed with laterally extending arms arranged to support the die against bearing surfaces so that it is free to centralise itself with respect to the coated wire or the like; when the latter issues through the apical orifice.

Preferably the conical cup member has a normally closed radial slit, which, when opened, enables the die to be inserted radially upon the wire. Thus one of the radial arms may comprise a pair of overlapping strips which are normally pressed resiliently together, but which when separated serve to open the slit in the cup member.

As a further aspect the invention provides a machine for continuously coating a wire or the like with a viscous medium, comprising in combination a container for medium through which the wire or the like is drawn in an upward direction, a die in the form of a substantially conical inverted cup having at its apex an orifice through which the wire or the like is drawn after leaving the bulk of the medium in the container, and supporting means carried by a plurality of arms extending outwards from the conical cup. Preferably a pair of sligned arms extend outwards from the conical cup at diametrically

opposite points and each is caused to engage a downwardly facing supporting surface as the die is borne upwards by the movement of the wire or the like and the tenacity of the applied coating medium, the die being free to move in a horizontal plane so as to centre the orifice with respect to the wire or the like.

The invention is illustrated by way of example in the accompanying drawing, in which:

10 Figure 1 is a side elevation of the die shown partly in section;

Figure 2 is a plan corresponding to Figure 1;

Figure 3 is a side sectional elevation of a coating machine utilising the improved dies; and

15 Figure 4 is a fragmentary front elevation showing the means used for retaining the dies.

Each of the dies, of which there are usually several in a single coating machine, takes the form shown in Figures 1 and 2 and comprises a strip 10 of bronze or other metal which is bent back upon itself, as shown in Figure 2, so as to form a loop 11 which constitutes a resilient hinge adapted to ensure that the two halves of the strip 10 lie flat upon one another and press firmly together. The free ends 12 and 13 opposite to the loop are conveniently splayed so that they lie apart and thus facilitate the opening of the die when it is desired to position the latter around the wire which is to be coated.

20 30 At a position midway between the loop 11 and the splayed ends 12 and 13 the two thicknesses of metal strip are spread apart, say in a press, to produce a diametrically divided substantially conical inverted cup 14, the apex 15 of which is

35 formed with an axial orifice 16 of predetermined diameter, the size being such as to produce the desired thickness of coating on a wire of prescribed diameter. The apex 15 preferably projects above the upper edge of the metal strip 10,

40 45 while the lower margin 17 in the form shown is disposed in a plane extending between the upper and lower edges of said strip 10. It will be seen that the strip 10 produces in effect a pair of radial arms 10a and 10b of substantially rectangular cross section spaced around the cup.

The preferred arrangement of coating machine for use with the improved form of die is shown in Figures 3 and 4. It comprises a casing 18 having a top 19, a rear wall 20, a lower front wall 21 and a pair of end walls, one of which is indicated at 22. The front wall 21 serves as a support for a pair of blocks 23 and 24 which are clamped in position by a plate 25 adapted to be tightened by a pair of butterfly nuts, one of which is shown at 26. The surface 27 of the

block 24 carries a layer 28 of resilient material such as compressed cork, while the adjacent surface of the block 23 is formed with a series of vertical grooves, one of which is shown at 29. These are for the passage of the wires which are to be coated, and which are indicated at 30, 31 and 32 in Figure 4. Thus the grooves 29 are closed by the layer 28 and prevent the leakage of coating medium in a downward direction past the wires. The blocks 23 and 24 are preferably composed of compressed fabric impregnated with synthetic resin or like material.

The coating medium is introduced in a constant stream through a duct 33 having part of its cross section extending through the rear wall 20, said duct being held in position by one or more clamps 34. The stream of coating medium passes through a number of orifices 35 to form a pool of medium, which is indicated at 36. The surface level of this pool can be regulated by means of a plate 37, which is fitted to a spindle 38 and is thus angularly adjustable, the surplus medium being allowed to flow between the walls 20 and 21 and return to a storage tank (not shown).

The dies, three of which are shown in the drawing at 39, 40 and 41 respectively, are carried by a bracket 42 which is substantially J-shaped in cross section and which has a horizontal flange 43 adapted to be clamped to the top 19 of the casing by means of a screw 44. The vertical limb 45 of the bracket is formed with three rectangular openings, one of which is shown at 46 in Figure 3, and at corresponding positions the short limb 47 has vertical parallel-sided notches, one of which is indicated at 48. When the machine is in use each die has its limb 10a inserted through the corresponding slot 46, while the limb 10b is retained in position within the notch 48 by a rectangular frame member 49, the upper and lower rails of which are indicated at 50 and 51 respectively. This frame member is hinged at 52 to the bracket 42 and is arranged to be held in its closed position by a catch 53. Each of the notches 48 is continued downwards, as at 54, in the form of a slot through which the wire 30 can be passed, but the lower portion of the bracket 42 has a relatively large hole 55, through which coating medium can pass upwards with the wire 30 and can simultaneously flow back into the pool 36. The opening in the casing in front of the dies 39, 40 and 41 is arranged to be closed by a readily removable cover 57, leaving a slot 58 through which the wires 30, 31 and 32 pass upwardly.

It will be seen that by moving the frame 49 forwards about its hinge 52 the dies 39, 40 and 41 can be placed in position around the wires 30, 31 and 32 by slightly separating the halves of the dies, the splayed ends of said dies then being inserted into the apertures 46 in the bracket 42. The frame 49 is then returned to its closed position so as to embrace the other limbs 10b of the dies. Thus the under surface of the rail 50 and the upper end surface 56 of each of the slots 46 serve as bearers for the arms of the die and enable the latter to slide freely in any direction horizontally so that said die can centre itself with respect to the corresponding wire. The centering action is brought about by the coating medium carried up by the wire being in excess of the quantity which is permitted to escape through the orifice 16 in the apex 15. This excess medium is deflected by the sloping sides of the inverted cup 14, thus causing the medium to

change its direction. This change of direction of the medium results in radial forces normal to the wire, which forces cause the die to move in a horizontal plane until the radial forces reach a state of equilibrium when the die is centralised about the wire. There is also a vertical component which causes the die to lift upon the column of medium and thus come into contact with the upper rail 50 of the frame and the upper end 56 of the slot 46. The sloping internal wall of the die efficiently centralises the die, for the conical cup has considerable depth, say $\frac{1}{8}$ inch, and is symmetrical in all directions about its vertical axis, i. e. about the axis of the wire. Moreover the frictional resistance to this centralising movement is relatively slight, as the die has only two points in contact with its supporting member, namely those parts of the arms 10a and 10b which bear against the upper rail 50 of the frame 49 and the upper end 56 of the slot 46 respectively. Also the robustness of the die enables it to be made relatively small and light so that it floats readily upon the ascending column of medium. If desired the level of the pool 36 of medium can be such that during working the two points at which the die is supported, namely at 50 and 56, are flooded with medium, since this keeps the parts lubricated and thus enables the die to move particularly freely; the medium, however, should not reach as high as the apex 15 of the die. Moreover in these circumstances a regular circulation of medium from the interior of the die back to the reservoir or storage tank is ensured, and this promotes efficient working by relieving the die of air bubbles and foreign matter, as well as by making sure that the wire is being coated with medium in a substantially uniform condition.

It will be appreciated that the invention is not limited to the example which has been described and that various modifications may be made. For instance, the conical die may be provided with only one radial supporting arm or with more than two, while alternative forms of supporting device may be used. Moreover, in some cases the die may depart from a truly conical shape; for instance its interior may be in the form of a pyramid having a base of hexagonal or other regular shape. Also the improved dies may be used in other forms of coating machine than that described.

What we claim is:

1. A die for regulating the thickness of viscous coatings applied to wires and the like, comprising an inverted cup member having a substantially conical interior and an orifice at its apex, said cup having a normally closed radial slit, which, when opened, enables the die to be inserted radially upon the wire, a plurality of arms radially extending from said cup to support the die against bearing surfaces, said arms being so spaced around the cup that the die is free to centralize itself with respect to the coated wire or the like when the latter issues through the apical orifice, one of said radial arms comprising a pair of overlapping strips which are normally pressed resiliently together, but which, when separated, serve to open the radial slit in the cup member.

2. A die for regulating the thickness of viscous coatings applied to wires and the like, comprising an inverted cup having a substantially conical interior and an orifice at its apex, said cup having a pair of arms radially extending in line from diametrically opposite parts of said cup to support the die against bearing surfaces so that the

die is free to centralize itself with respect to the coated wire or the like when the latter issues through the apical orifice.

3. A die for regulating the thickness of viscous coatings applied to wires and the like, comprising an inverted cup having a substantially conical interior with an orifice at its apex, said cup having a pair of arms radially extending in line from diametrically opposite parts of the cup member to support the die against bearing surfaces, both of the radial arms being split longitudinally, the parts at the outer extremity of one arm being joined to constitute a resilient hinge while at the outer end of the other arm the parts are shaped so that they lie apart and facilitate the opening of the cup member, which cup member is split adjacent each of said pair of radial arms.

4. A die for regulating the thickness of viscous coating applied to wires and the like, comprising an inverted cup having a substantially conical interior and an orifice at its apex, said cup having a plurality of arms radially extending therefrom to support the die against bearing surfaces, said arms being so spaced around the cup that the die is free to centralize itself with respect to the coated wire or the like, when the latter issues through the apical orifice, each of said arms being of flat, rectangular cross section, with that edge which faces the direction of travel of the wire disposed in advance of the apical orifice.

5. A die for regulating the thickness of viscous coatings applied to wires and the like, comprising an inverted cup having a substantially conical interior and an orifice at its apex, said cup having a normally closed radial slit which, when

opened, enables the die to be inserted radially upon the wire and a pair of arms radially extending in line from diametrically opposite parts of said cup to support the die against bearing surfaces so that the die is free to centralize itself with respect to the coated wire or the like when the latter issues through the apical orifice.

6. A die for regulating the thickness of viscous coating applied to wires and the like, comprising an inverted cup having a substantially conical interior and an orifice at its apex, said cup having a pair of arms radially extending in line from diametrically opposite parts of said cup to support the die against bearing surfaces so that the die is free to centralize itself with respect to the coated wire or the like when the latter issues through the apical orifice, each of said arms being of flat, rectangular cross section, with that edge which faces the direction of travel of the wire disposed in advance of the apical orifice.

7. A die for regulating the thickness of viscous coatings applied to wires and the like, comprising an inverted cup having a substantially conical interior and an orifice at its apex, said cup having a pair of arms radially extending in line from diametrically opposite parts of said cup to support the die against bearing surfaces so that the die is free to centralize itself with respect to the coated wire or the like when the latter issues through the apical orifice, each of said arms being of flat, rectangular cross section, with that edge which faces the direction of travel of the wire disposed in advance of the apical orifice, said cup having a radial slit which, when opened enables the die to be inserted radially upon the wire.
